UNITED STATES PATENT OFFICE.

HENRY SCHELLER, OF BROOKLYN, NEW YORK.

SASH-VENTILATOR.

No. 831,479.

Specification of Letters Patent.

Patented Sept. 18, 1906.

Application filed April 24, 1906. Serial No. 313,468.

To all whom it may concern:

Be it known that I, HENRY SCHELLER, a citizen of the United States of America, residing at Brooklyn, in the county of Kings 5 and State of New York, have invented new and useful Improvements in Sash-Ventilators, of which the following is a specification.

This invention relates to improvements in sash-ventilators, the object of the invention 10 being to provide a simple and effective construction of ventilator which may be readily applied to sashes of ordinary construction and opened to any desired degree to secure free ventilation of a room without creating a 15 draft.

In the accompanying drawings, Figure 1 is an inside elevation showing the application 20 of the invention to one of the sashes of a window. Fig. 2 is a cross-section on line 2 of Fig. 1. Fig. 3 is a plan view of the ventilator.

Referring to the drawings, 1 designates a window-sash having a ventilation-opening 2, which may be formed by removing one of the panes of the sash or in any other preferred 25 manner. A closure is provided for controlling the opening 2, said closure comprising companion inner and outer shutters 3 and 4. Each of these shutters is formed of a frame having an opening for the reception of a 30 transparent pane 5, retained in position by suitable flanged keepers 6. These panes allow of the entrance of light through the closure when either of the shutters is in closing position.

The shutters 3 and 4 have their frame portions united at their lower ends by a union 7, which is provided with bearing-sleeves 8, revolvably mounted on a pivot-rod 9, arranged at the base of the opening 2. From the union 7 40 the shutters 3 and 4 extend upwardly in divergent relation and are connected and braced adjacent their upper ends by cross pieces or braces 10, joining the side portions thereof. Each shutter is also provided at its upper end with a handle or finger-piece 11 for convenience in adjusting the closure, said handles being adapted to enter receiving-recesses 12 in the upper wall of the opening 2 to allow the shutters to tightly close the opening.

It will be observed that the shutters are so arranged that upon swinging the closure as a whole inwardly or outwardly the shutter 3 or the shutter 4 may be brought into position to 55 close the opening 2 and adjusted to regulate

the size of the same, so as to permit of the entrance of more or less air into a room. A locking-bar 13 is pivoted at its outer end to the outer shutter 4, as shown at 14, and provided at its inner end with a suitable handle 60 or finger-piece 15, extending through and movable within a slot in the frame of the inner shutter 3. The lower edge of the bar 13, which is curved to conform with the arc of movement of the closure, is formed with 65 spaced recesses or teeth 16, adapted to engage a locking-pin 17 on one of the side walls of the opening 2, whereby the shutter may be conveniently locked in any desired position of adjustment.

Fig. 2 shows in full and dotted lines the closure adjusted to an intermediate open position and to a position in which the inner shutter 3 closes the opening 2, and it will be apparent that upon swinging the closure inward 70 the shutter 4 may be brought into position to close the opening. When the closure is in open position, the air from the exterior flows downward through the space between the sash and outer shutter 4 and thence into 75 the room through the spaces between the shutter and sides and top of the inner shutter 3, thus preventing the passage of a direct draft of air across the room. In other words, the shutter 3 will act as a deflector to break 80 up or diffuse the entering current of air and prevent it from sweeping across the room in an unbroken current.

The ventilator may be employed for general purposes to control a ventilation-opening 90 in any type of structure and may be applied to a window-sash of ordinary construction by simply removing one of the panes from the sash and substituting the ventilating device in its place.

Having thus described the invention, what 95 is claimed as new is—

1. The combination with a sash or other structure having a ventilation-opening, of a closure therefor comprising shutters pivoted 100 to swing in unison and projecting beyond opposite sides of the opening, and means for holding the closure in a desired adjusted position.

2. The combination with a sash or other structure having a ventilation-opening, of a closure therefor comprising divergently-arranged shutters pivotally mounted at their convergent ends and connected to swing in 105 unison, said shutters being arranged upon op- 110

posite sides of the opening, and means for holding the closure in a desired adjusted position.

3. The combination with a sash or other structure having a ventilation-opening and a locking member upon one of the walls of the opening, of a closure therefor comprising shutters pivoted to swing in unison and projecting beyond opposite sides of the opening, and a rack carried by the closure and adapted to be engaged with said locking member to hold the closure in a desired adjusted position.

4. The combination with a sash or other structure having a ventilation-opening and a pivot-rod at the base of the opening, of a closure therefor comprising shutters arranged in divergent relation and connected for movement in unison, said shutters being arranged on opposite sides of the opening and pivoted at their convergent ends to said rod, and means for connecting the upper end of the closure at any point between the shutters to the sash or structure.

25 5. The combination with a sash or other

structure having a ventilation-opening and a locking projection, of a closure pivotally mounted in said opening and comprising oppositely-arranged companion shutters connected to swing in unison, and a curved rack-bar pivoted to one of the shutters and having a handle extending through the other shutter, whereby the closure may be engaged with the locking projection to hold the closure in any desired adjusted position.

30 6. A ventilating device comprising a pair of divergently-arranged shutters connected to move in unison and pivotally mounted at their convergent ends, and a fastening member extending between the divergent ends of the shutters for engaging a complementary fastening member to secure the device in a desired adjusted position.

35 In testimony whereof I affix my signature in presence of two witnesses.

HENRY SCHELLER.
